UNITED STATES PATENT OFFICE.

JACOB YOUNGMAN, OF SUNBURY, PENNSYLVANIA, ASSIGNOR OF ONE-HALF
TO JONATHAN M. BASTIAN, OF SAME PLACE.

BALANCED SLIDE-VALVE.

SPECIFICATION forming part of Letters Patent No. 392,578, dated November 6, 1888.

Application filed January 24, 1888. Serial No. 261,732. (No model.)

To all whom it may concern:

Be it known that I, JACOB YOUNGMAN, a citizen of the United States, residing at Sunbury, in the county of Northumberland and 5 State of Pennsylvania, have invented certain new and useful Improvements in Balanced Slide-Valves for Steam-Engines; and I do hereby declare the following to be a full, clear, and exact description of the invention, such as will 10 enable others skilled in the art to which it app pertains to make and use the same.

This invention relates to valves of that class known as "balanced slide-valves;" and it has for its object to provide a more perfectly-balanced valve of simple and cheap construction 15 which shall effectually prevent the leakage of steam from the chest to the back of the valve, thus relieving the same of the downward pressure, which is common in the ordinary D-valve 20 and which is the occasion of much wear of the valve and seats for the same; and it consists of the parts and combinations of parts herein-after described and claimed.

In the accompanying drawings, forming a 25 part of this specification, Figure 1 is a longitudinal central section through my improved valve and steam-chest; Fig. 2, a vertical cross-section through the same; Fig. 3, a detail view of the valve proper, showing the arrangement of the 30 packing-strips; Fig. 4, a detail view of the bearing cap or frame for the valve, and Fig. 5 a perspective view of one of the packing-strips.

Similar letters refer to similar parts throughout the several views.

A represents a portion of the cylinder for the piston of an engine, provided with the usual steam-ports, *a*, and exhaust-port *b*. On the cylinder the steam-chest *B* is secured in the 40 usual or any desired manner over the ports *a* *b*. On the chest is secured a lid, *C*, having a bonnet or arched head, *D*, as clearly shown in Fig. 2, in which the balance-plate *E* is adjustably suspended by means of screw-bolts *c*, passing 45 through the bonnet and into lugs formed on the back of the plate. By this construction of the head *D*, I secure increased capacity of the chest, as I am enabled to locate the plate *E* entirely within the arched head.

50 The valve *F* is provided with the usual exhaust-cavity, *d*, but differs from all other valves

with which I am familiar in that it is cast hollow or box-shaped, thus providing a chamber, *e*, within its walls *f*, as clearly shown in Fig. 3. At about the center of the upper surface 55 or top of the wall *f*, I insert short studs or pins *g* at suitable distances apart, there being, preferably, two pins in each side and end wall.

G represents the metallic packing-strips, having slots *h* formed in their sides corresponding to the pins *g* in number and location, so that they may be fitted on top of the walls with the slotted sides of the strips being outward. The strips constitute an extension of the walls of 65 the valve, but are movable laterally or inwardly on the tops of said walls. As shown most clearly in Fig. 5, these strips taper toward their lower sides, so that they are narrower than the upper surface of the walls on 70 which they rest.

The object of thus reducing the strips is to obviate the tendency they would have to hold the overlapping rim or flange *m* of the bearing-cap or rectangular frame *H* if the two sides 75 were equal, and thus destroy the freedom of movement which the cap should have. It will also be seen, on reference to Fig. 3, that the side walls of the valve have cleats *n* cast on their inner sides, the object of which is to give 80 a clearance for the tool in dressing said sides to a fit for the downwardly-projecting walls *o* of the bearing-cap. This cap is formed of a rectangular frame having the walls *o* and rim or overlapping flange *m* and a cross-piece, *p*, 85 provided with a downwardly-extending pin, *r*, said cross-piece being located with its upper surface below the top of the cap, so that it cannot form part of the abrasive surface.

A spring, *M*, is placed within the chamber 90 *e* so that it will exert its pressure upwardly against the cross-piece *p* to raise the bearing-cap up against the balance-plate when steam is shut off, and also give the necessary elasticity to the cap and valve. The spring shown 95 is an ordinary flat bow-spring having a perforation at its center, through which the pin *r* projects to guide and steady said spring; but it may be, if desired, a spiral spring surrounding the pin. The cap *H* is fitted or is telescoped within the chamber *e* of the valve, filling 100 the same closely, and its rim *m* rests on

the strips *G* and projects outwardly beyond the same. The bottom of the valve is also provided with flanges *s* on its four sides, as shown. The perforation *w* in the center of the bottom of the valve is for the purpose of giving an outlet to any steam which may get back of the valve or in its chamber through the exhaust-port.

In operation the steam is admitted to the chest, and from thence to the ports *a* in the usual manner, and exhausts from the cylinder through port *b*, and thence to the air or a condenser, as desired. The steam in the chest, however, exerts a powerful lateral pressure on the strips, forcing them in closely against the walls *o* of the bearing-cap, and also lifting the said bearing-cap up against the balance-plate by the pressure which is exerted against the under side of its rim, while at the same time it exerts a downward pressure on the upper surface of said strips, causing the latter to closely hug the walls of the valve, thus closing the joint between the walls and strips by the downward pressure and the joint between the walls *o* of the bearing-cap and the strips by the lateral pressure on the latter, and finally closing the joint between the balance-plate and the cap by the upward pressure of the steam on the rim or flange of said cap, and preventing the admission of live steam to the back of the valve.

Having thus described my invention, what I claim as new, and desire to secure by Letters Patent, is—

35 1. The combination, with the steam-chest having an arched head or lid and a balance-plate adjustably secured within said head, of the valve having a chamber formed in its body, the pins rigidly secured to the walls of said

chamber, the metallic strips having slots in their sides resting on said walls, the rectangular bearing-cap fitted within said chamber and having the overlapping rim, the cross-piece having the downwardly-projecting pin, and a spring guided and steadied by said pin and bearing against said cross-piece, substantially as described.

2. The combination, in a balanced slide-valve, of the valve having the chamber formed in its body, the cleats formed in the walls of said chamber, the pins or studs rigidly secured in said walls, the metallic packing-strips having slots formed in their sides, the bearing-cap having the downwardly-extending walls and projecting rim, the cross-piece provided with a downwardly-projecting pin, and the spring located within said chamber and exerting its pressure against said cross-piece, substantially as described.

3. The combination, in a balanced slide-valve, with a suitable steam-chest and balance-plate, of a valve having a chamber formed in its body, the pins rigidly secured in the walls of said chamber, the tapering metallic strips having slots formed in their sides, the bearing-cap having the outwardly-projecting rim and downwardly-extending walls, the cross-piece having the downwardly-projecting pin, and a spring bearing on the bottom of said chamber and against said cross-piece and guided and steadied by said pin, substantially as described.

In testimony whereof I affix my signature in presence of two witnesses.

JACOB YOUNGMAN.
